(57) **CLAIM**

The ornamental design for a hair styling device holster, as shown and described.

DESCRIPTION

FIG. 1 is an isometric view of the hair styling device holster; FIG. 2 is a front side view of the hair styling device holster; FIG. 3 is a rear side view of the hair styling device holster; FIG. 4 is a side view of the hair styling device holster; FIG. 5 is a side view that is opposite the side view of FIG. 4 of the hair styling device holster; FIG. 6 is a top side view of the hair styling device holster; and, FIG. 7 is a bottom side view of the hair styling device holster. The broken lines illustrate portions of the hair styling device holster and form no part of the claimed design.

1 Claim, 7 Drawing Sheets
